227,676

ANTENNA FOR RADIO RECEIVER

Takeshi Okada, Hirakata, Japan, assignor to Matsushita
Electric Industrial Co., Ltd., Osaka, Japan

Filed Dec. 23, 1971, Ser. No. 211,829

Claims priority, application Japan June 25, 1971

Term of patent 14 years

Int. Cl. D14—02

U.S. Cl. D26—14 F

FIG. 1 is a rear and left side perspective view of an antenna for radio receiver showing my new design,

FIG. 2 is a front and right side elevational view, and
FIG. 3 is a rear and left side perspective view thereof showing the side cap removed.

I claim:

The ornamental design for an antenna for radio receiver, as shown and described.

References Cited

UNITED STATES PATENTS

D. 155,093	9/1949	Leonard	-----	D26—14
D. 181,952	1/1958	Adams	-----	D26—14 X
D. 182,229	3/1958	Ferman	-----	D26—14 X
3,385,393	5/1968	Gold	-----	181—31

BERNARD ANSHER, Primary Examiner